(57) **CLAIM**

The ornamental design for a pneumatic tire, as shown and
described.

DESCRIPTION

FIG. 1 is a perspective view of a pneumatic tire showing my
new design, it being understood that the tread pattern repeats
throughout the entire outer circumference;

FIG. 2 is a partial end view thereof, shown at an enlarged
scale;

FIG. 3 is an end elevation view thereof; and,

FIG. 4 a side elevation view thereof; the opposite side elevation
view being identical thereto.

The broken lines in FIG. 2 show the boundaries of the figure
and form no part of the claimed design.
